UNITED STATES PATENT OFFICE.

EDWIN O. PRESBY, OF NEW YORK, N. Y.

GARMENT-SUPPORT.

SPECIFICATION forming part of Letters Patent No. 761,605, dated May 31, 1904.

Application filed February 16, 1904. Serial No. 193,843. (No model.)

To all whom it may concern:

Be it known that I, EDWIN O. PRESBY, a citizen of the United States, residing at New York city, State of New York, have invented 5 certain new and useful Improvements in Garment-Supports; and I do hereby declare the following to be a full, clear, and exact description of the invention, such as will enable others skilled in the art to which it appertains to make 10 and use the same.

My invention relates to improvements in garment-supports.

The object of my invention is to produce a simple, effective, and inexpensive combination 15 undergarment-support and one that can be readily applied to trousers and as to which there is no danger of its becoming loose.

With these objects in view my invention consists in the construction and combinations 20 of parts as hereinafter described and claimed.

In the accompanying drawings, Figure 1 is a perspective view of my device as applied to trousers and undergarments. Fig. 2 is a back view of the device. Fig. 3 is a similar view 25 of a modification. Fig. 4 is a side view of the same, showing the trousers in section; and Fig. 5 is a back view of a modified form.

a represents a small metal plate of about the size of an ordinary button. It is provided 30 with an extension *b* on its lower edge, which is perforated to receive the end *c* of a hook *d*, preferably made of spring-wire and adapted to close upon itself. The disk *a* may be provided with a single hole *e*, as shown in Fig. 3, 35 or a plurality of holes *f*, as shown in Fig. 2. This disk may be flat, as shown in Fig. 2, or concaved, as shown in Fig. 5.

g represents a portion of the trousers, and *h* represents a portion of the undergarment 40 provided with the usual loop *i*.

j represents the ends of the ordinary suspenders, and *k* the ordinary suspender-button.

In attaching my improved device to the trousers the plate *a* is placed on the inside of the trousers, and this plate and the button are 45 secured to said trousers by sewing through the holes *f*. In case, however, machine-made shank-buttons are used, instead of a plurality of holes *f* I use a single hole *e*, through which the shank of the button is passed. The 50 loop *i* is then brought up over and dropped into the portion *d* of the spring-wire, which closes and holds the undergarment in the proper position.

The spring-wire *d* is pivotally supported on 55 the disk *a* so that it may move freely over to one side or the other, or even back and forth if desired, so that it will automatically adjust itself to meet varying conditions, while preventing the loop *i* from being disengaged 60 therefrom.

Having thus described my invention, what I claim as new, and desire to secure by Letters Patent of the United States, is—

In a garment-support, the combination with 65 an ordinary button, of a perforated disk adapted to be attached thereto, said disk being provided with a perforation on its lower edge and a looped spring-wire provided with a hook in one of its ends, which hook passes through the 70 perforation on the lower edge of said disk, substantially as described.

In testimony whereof I affix my signature in presence of two witnesses.

EDWIN O. PRESBY.
